CANDLE TRIMMER

Vincent S. Lippe, Bronxville, N.Y., assignor to Silvestri Art Manufacturing Co., a corporation of Texas

Filed Aug. 8, 1966, Ser. No. 3,387

Term of patent 14 years

(Cl. D48—2)

FIG. 1.

FIG. 2.

The broken line showing of a candle and candle holder in FIG. 1 is for illustrative purposes only.

I claim:

The ornamental design for a candle trimmer, as shown and described.
